UNITED STATES PATENT OFFICE

GROSVENOR N. ALLEN AND MARY G. PARKER, OF ONEIDA, AND CHARLES MATLACK PRICE, OF GRAND VIEW, NEW YORK, ASSIGNEES TO ONEIDA COMMUNITY, LIMITED, OF ONEIDA, NEW YORK, A CORPORATION OF NEW YORK

DESIGN FOR A SPOON OR SIMILAR ARTICLE

Application filed July 11, 1930. Serial No. 36,324. Term of patent 14 years.

To all whom it may concern:

Be it known that we, GROSVENOR N. ALLEN and MARY G. PARKER, citizens of the United States, residing at Oneida, county of Madison, State of New York, and CHARLES MATLACK PRICE, citizen of the United States, residing at Grand View, Rockland County, State of New York, have invented a new, original, and ornamental Design for a Spoon or Similar Article, fully described and represented in the following specification and the accompanying drawing, forming a part of the same, and showing a spoon embodying the design, the essential feature of which is

the ornamentation on the front face thereof.

In said drawing Figure 1 is a front view, Figure 2 is a fragmentary rear view, and Figure 3 a cross-sectional view on line 3—3 of Figure 1.

We claim:

The ornamental design for a spoon or similar article as shown and described.

In testimony whereof we have hereunto set out hands.

GROSVENOR N. ALLEN.
MARY G. PARKER.
C. MATLACK PRICE.
